[57] CLAIM

The ornamental design for the night vision scope, as shown and described.

DESCRIPTION

FIG. 1 is a side elevational view of the night vision scope, showing my new design;

FIG. 2 is a top plan view of the night vision scope;

FIG. 3 is a bottom plan view of the night vision scope;

FIG. 4 is a side elevational view of the night vision scope from the opposite side of the night vision scope

illustrated in FIG. 1;

FIG. 5 is an end elevational view of the night vision scope looking from left to right in FIG. 1;

FIG. 6 is an end elevational view of the night vision scope looking from right to left in FIG. 1;

FIG. 7 is a side elevational view of the night vision scope illustrated in FIG. 1 and illustrated with an optical filter covering the end of the scope;

FIG. 8 is a side elevational view of the night vision scope illustrated in FIG. 7 and illustrating the scope with the filter in a retracted position; and

FIG. 9 is an end elevational view of the night vision scope with the filter covering the end of the scope and looking from left to right in FIG. 7.
